(57) **CLAIM**

The ornamental design for an adaptor for sample rack, as shown and described.

DESCRIPTION

FIG. 1 is a front and top perspective view of an adaptor for sample rack according to the design;
FIG. 2 is a front, top, and right side perspective view thereof;
FIG. 3 is a front, top, and left side perspective view thereof;
FIG. 4 is a front elevational view thereof;
FIG. 5 is a rear elevational view thereof;
FIG. 6 is a right side elevational view thereof;
FIG. 7 is a left side elevational view thereof;
FIG. 8 is a top plan view thereof;
FIG. 9 is a bottom plan view thereof;
FIG. 10 is a cross-sectional view taken along line 10-10 of FIG. 4;
FIG. 11 is a cross-sectional view taken along line 11-11 of FIG. 4;
FIG. 12 is a cross-sectional view taken along line 12-12 of FIG. 8; and,
FIG. 13 is a cross-sectional view taken along line 13-13 of FIG. 8.
